COLLECTOR-IONIZER ELECTRODE

Joseph F. Valvo, Stillwater, Okla., and Peter Hodson, Wellsville, N. Y., assignors to Apra Precipitator Corporation, New York, N. Y., a corporation of Delaware

Application July 27, 1955, Serial No. 524,637

5 Claims. (Cl. 183—7)

This invention relates generally to an arrangement for maintaining a rod-like member concentrically positioned within an outer cylinder of revolution, and more particularly it relates to an ionizer-collector electrode adapted for use in an electrostatic precipitator, and an arrangement whereby said electrode is positively positioned centrally within a concentric outer collecting surface.

In order to permit the employment of maximum voltage in the electrodes creating an electrostatic field without arcing across the space between electrodes, it is imperative that there be no localized projecting portions on the electrodes which might induce arcing and subsequent loss of collecting efficiency. In the case of cylindrical inner and outer members as are frequently utilized in electrostatic precipitators, the annular space between cylindrical members must be maintained at a constant dimension, and in the case of circular inner and hexagonal outer members, the annular space must be kept constant as viewed from a vertical plane extending through the center of the inner member and the flat sides of the hexagonal outer member.

It thus becomes a general object of our invention to provide an electrode arrangement of the character described which is simple and easy to install or replace and yet is positively positioned so that the inner electrode member is at all times concentrically held within the outer collecting surface.

It is a more specific object of our invention to provide a flexible mounting arrangement for a collector-ionizer electrode whereby said electrode will not be subject to misalignment or bowing within a concentric outer member.

These and other objects of our invention have been attained by providing flexible mounting devices at opposite ends of the ionizing electrode member so that compressive or transverse stresses may not be transmitted to the collecting electrode to effect bowing or other distortion thereof.

How these objects and advantages of our invention are attained will be more readily understood by reference to the following description and the annexed drawing in which:

Figure 1 is a fragmentary view taken inside a precipitator housing showing in elevation a tubular collecting surface with a collector-ionizer electrode constructed according to this invention.

Figure 2 is a modified form of flexible mounting means for the ionizing electrode.

Grid members 10 and 11 are made integral with collecting cylinder 12 by means of intermediate insulators diagrammatically illustrated at 29 which maintain the grid members spaced apart a fixed distance so they may serve as a positive support for the collector-ionizer electrode 13, 15.

The collector-ionizer electrode is suspended at one end from upper grid member 10 and is guided at its opposite extremity by a lower grid member 11. The electrode is at all times normal to the planes of the spaced grid members, and it is understood that this assembly is mounted

2

within an enclosing housing having gas inlet and outlet openings which permit a stream of gas to flow therethrough substantially parallel to the suspended collector-ionizer electrodes. Details of the housing and the gas inlet and outlet means are not illustrated because they represent no part of the invention but reference may be made to Patent No. 2,582,133 for disclosure of one type of housing to which the device of this invention is readily adaptable.

10 Each electrode assembly comprises a cylindrical collector section 13 pivotally suspended at its upper end from an upper grid member 10. The lower end of the collecting electrode 13 is removably connected to a make-up stub 14 forming an end portion of the ionizing electrode assembly while the ionizing electrode 15 with its ionizing discs 16 is connected to the make up stub 13 by means of a laterally pivotal joint 17. This joint may take the form of one or a plurality of strands of laterally flexible wire as shown in Figure 1, a coiled wire member 18 as shown in Figure 2, or any one of several non-illustrated forms such as a chain-like linking member, a pivoted pin type universal joint or a ball type universal joint. A similar laterally flexible joint 17 connected to the lower end of ionizing electrode 15 provides a connecting link between the electrode and an adjusting link 19 which has a threaded portion 20 extending through an opening 21 in the lower grid 11 whereby an adjusting nut 22 screwed against an intermediate spring 23 places a tension upon the electrode assembly lying intermediate 30 the spaced grid members.

In the form illustrated in Figure 1, the upper portion 24 of collecting electrode 13 is necked down to pass through an opening 25 in grid 10 which is in alignment with the opening 21 in lower grid 11. A pivot member 35 26 with a convex face providing a ball-type friction surface is fixed to the end of the collecting electrode which extends through opening 15 in grid 1. The member 26 is preferably fixed to the collecting electrode by means readily removable as is illustrated by pin 28 of Figure 1.

40 In a collector-ionizer electrode of the type herein defined, the ionizer portion comprising the disc bearing section 15 is first provided at opposite ends with laterally flexible members 17. Top member 17 is attached to make-up stub 14 which is in turn adapted to be removably attached to collecting electrode 13. Link 19 is provided with a diameter less than that of opening 21 to permit it to pass freely therethrough. Upper end portion 24 of collecting electrode 13 is necked down to a diameter similar to that of link 19 to permit its passage through 50 opening 25 in grid 10. It is to be noted that the diameter of opening 25 is considerably larger than that of neck 24 to permit substantial lateral re-alignment.

In assembling a unit comprising a collector-ionizer electrode concentrically positioned within a cylindrical collecting surface 12 of the type illustrated, the collecting surface is first arranged to rest upon insulators 29 which support it concentric with respect to openings 21 and 55 25 in the spaced grid members. It is to be understood the insulator supports 29 are an illustrative embodiment only

60 since in practice a large number of collecting tubes are combined and supported as a unitary body by insulators positioned only at infrequent intervals. The complete electrode assembly is then lowered into each collecting tube 12 so neck 24 thereof may be inserted through opening 25 in grid 10 where it is adapted to receive convex 65 pivot member 26 which is linked thereto by a cotter pin 28 or other linking means. The opposite end of the electrode assembly comprising connecting link 19 is inserted through opening 21 in the lower grid 11, so the entire electrode assembly may be brought under tension by a force applied through spring 23 as induced by nut 22. When under tension in the manner above described,

lateral or axially compressive forces may be applied to the electrode and grid assemblies without causing bowing of the electrodes or other deformation thereof which might promote arcing and subsequent loss of collecting efficiency.

A suitable source of high voltage direct current is supplied to the collector-ionizer electrode assembly through the electrically conductive grid members. Since the collecting cylinder is insulated from the electrode assembly, it may be grounded to provide an electrostatic cell as illustrated by Figure 1. In practice a multiplicity of similar cells are placed in juxtaposition to provide gas cleaning capacity for any predetermined quantity of gas flow.

What we claim is:

1. In an electrostatic precipitator having a support grid and a guide grid spaced apart in parallel planes, an electrode assembly intermediate said grid members comprising a collecting electrode pivotally suspended from the support grid; an ionizing electrode axially aligned with the collecting electrode and pivotally connected thereto; a collecting surface positioned concentrically around said electrode assembly and insulated therefrom; and resilient connecting means interconnecting said ionizing electrode and said guide grid whereby the collector and ionizer components of the electrode assembly are maintained in axial alignment.

2. In an electrostatic precipitator having a support grid and a guide grid spaced apart in parallel planes, an electrode assembly intermediate said grid members comprising a cylindrical collecting electrode pivotally suspended from the support grid; an ionizing electrode axially aligned with the collecting electrode and having one end pivotally attached thereto; an adjusting link pivotally attached to the axially spaced end of said ionizing electrode; and resilient connecting means interconnecting said adjusting link and said guide grid arranged whereby the collector and ionizer components are maintained under constant tension.

3. In an electrostatic precipitator having a support grid and a guide grid spaced apart in parallel planes, an electrode assembly intermediate said grid members comprising a collecting electrode pivotally suspended from the support grid; an ionizing electrode axially aligned with the collecting electrode and having an end pivotally connected thereto; an adjusting link pivotally attached to the axially spaced end of said ionizing electrode; a collecting surface positioned around said electrode assembly and insulated therefrom; and resilient connecting means interconnecting said ionizing electrode and said guide grid whereby the electrode assembly is maintained under tension in axial alignment within the concentric collecting surface.

4. An electrostatic precipitator having a support grid and a guide grid spaced apart in parallel planes; an electrode assembly intermediate said grid members comprising a collecting electrode pivotally suspended from the support grid; an ionizing electrode axially aligned with said collecting electrode; an adjusting link axially aligned with said ionizing electrode and resiliently mounted on said guide grid; and pivotal extending means interconnecting axially remote ends of the ionizing electrode to the collecting electrode and to the adjusting link.

5. An electrostatic precipitator as defined in claim 4 wherein the pivotal connecting means comprises flexible wire members axially parallel to the ionizing electrode.
